UNITED STATES PATENT OFFICE.

ELIAS LUGINBUHL, OF NORWOOD, OHIO.

STEAM-ENGINE.

1,132,782.

Specification of Letters Patent. Patented Mar. 23, 1915.

Application filed June 10, 1914. Serial No. 844,233.

To all whom it may concern:

Be it known that I, ELIAS LUGINBUHL, a citizen of the United States, residing at Norwood, in the county of Hamilton, State of Ohio, have invented certain new and useful Improvements in Steam-Engines; and I do hereby declare the following to be a full, clear, and exact description of the invention, such as will enable others skilled in the art to which it appertains to make and use the same.

This invention relates to steam engines, more particularly to that type of engines in which the cylinder and piston are independently movable.

The object of the present invention is the provision of an improved engine of this type so constructed that the loss of power occasioned by the pressure upon the stationary cylinder heads will be reduced to a minimum; thereby obviating the great disadvantage of the detrimental vibration caused by such loss.

An important object is to provide an engine of this character in which a portion of the steam is utilized for serving as a pneumatic buffer to muffle or deaden the shock of the main impact of the moving parts.

More specifically an object of the invention is to provide an engine having a minimum number of parts and especially employing only a single valve operating means, the single valve being adapted to control the inlet and exhaust of steam from and to all ports in the device.

Other objects of this invention, such as comparative simplicity, durability, ease of operation, and maximum efficiency in service, together with the general improvement of the art, will be carefully brought out in the following description and illustrated in the accompanying drawings, in which—

Figure 1 is a top plan view of my engine; Fig. 2 is a side elevation thereof; Fig. 3 is a vertical sectional view, through the stationary cylinder and all the parts associated therewith and showing the cylinder and piston at one extremity of their stroke; Fig. 4 is a similar view with the movable cylinder and piston at the other extremity of their stroke; Fig. 5 is a horizontal sectional view showing the controlling valve and its associated parts in top plan; Fig. 6 is a vertical cross sectional view along the line 6—6 of Fig. 4; Fig. 7 is a cross sec-

tional view on the line 7—7 of Fig. 5, and, Fig. 8 is a similar view on the line 8—8 of Fig. 5; Fig. 9 is a perspective view of the valve detached, and, Fig. 10 is a rear view of the main cylinder with the valve casing attached.

Referring more particularly to the drawings, the numeral 10 designates the supporting base or bed of my improved engine upon the forward end of which is journaled a crank shaft 11 provided with cranks 12 and 13 and also provided with the usual flywheel 14. On the other end of the bed 10 is a stationary guide cylinder 15 which is closed at its outer end by a head 16 and at its inner end by a head 17 provided with packing glands 18 and 19, for a purpose to be described. Upon the lower side of the stationary cylinder 15 is provided a valve casing 20 within which is mounted a valve for controlling the inlet and outlet of steam in the engine.

A reciprocating cylinder 21 is disposed within the cylinder 15 and is provided with a piston rod 22 which extends through the gland 18 and is connected with the crank 13. Upon its lower side the cylinder 21 is provided with passages 23 and 24 which communicate with the interior of the cylinder 21 through ports 25 and 26. As the cylinder 21 slides back and forth within the cylinder 15 its heads 29 and 30 are adapted to cover and uncover ports 27 and 28 in the lower side of the cylinder 15. The cylinder 15 is provided with ports 31 and 32 communicating with the passages 23 and 24, respectively.

A piston 33 is slidably mounted within the cylinder 31 and has secured thereto a piston rod 34 which extends forwardly and is connected with the crank 12 after passing through the gland 19 in the head 17 and a similar gland 35 in the head 29 of the cylinder 21. These glands are solely for the purpose of forming perfectly steam-tight joints. As the piston 33 slides back and forth within the cylinder 21 it is adapted to cover and uncover the ports 25 and 26.

The valve casing 20 is provided with a cylindrical opening 36 extending transversely of the axle of the cylinders within which is revolubly mounted a valve, designated as a whole by the numeral 37. A steam inlet pipe 38 communicates with a passage 39 formed through the casing 30 and communicating with the opening 36.

Referring more particularly to Fig. 5 in the drawings, the numeral 40 designates a steam passage communicating with the port 27 and with a port 41 communicating with the opening 36. The numeral 42 designates a similar passage communicating with the port 28 and a port 43 communicating with the opening 36. Other ports 44 and 45 also communicate with the opening 36. The 10 casing 20 is further provided with ports 46 and 47 communicating with the ports 31 and 32, respectively. The valve 37 is provided with a plurality of passages for controlling the passage of steam through the 15 ports just described and the arrangement and formation of these passages will be brought out in the description of the operation, for the sake of clearness. The casing 20 is further provided with exhaust 20 ports 48 and 49 formed through its lower wall and communicating with the opening 36 and with an outlet pipe 50.

The valve 37 is provided in alignment with the port 43 with a passage 51 extending over half way of the periphery of the valve. A similar passage 52 is formed in the opposite end of the valve 37 and in alignment with the port 41, the passage 52 being disposed at substantially right angles 30 to the passage 51. The valve 37 is also provided intermediate its ends with a spiral passage 53 extending substantially three-fourths the way around the valve.

The operation of the engine is as follows: 35 Assuming that the cylinder 31 and piston 33 are in the positions shown in Fig. 3 of the drawings, the valve 37 is turned by mechanism to be described, to bring the passage 53 into registration with the steam inlet passage 39 and the port 46, whereupon steam will pass from the pipe 38, through the passage 53, port 46, and port 31, into the passage 23, and thence into the cylinder 21 behind the piston 33, thereby forcing the piston 33 rearwardly and forcing the cylinder 21 forwardly. As the cylinder and piston move as described, exhaust steam in advance of the piston 33 will be forced through the 40 port 26, into the passage 24, and thence through the port 32 and into the passage 54, whence it will pass through the port 44 and into the port 43 whence it will be carried through the passage 51, registering with the exhaust port 48 and outwardly through the 45 pipe 50. At the same time, steam in advance of the cylinder 21 will be forced through the port 27, passage 40, port 41, through the passage 52, in the valve 37, and out through the exhaust port 49. The 50 intake valve passage is so formed that the inlet ports 46 and 47 will be closed when the engine has made three-fourths of its stroke, and the exhaust ports 41, 43, 44 and 45 will stay open to nearly the end of the stroke, 55 thereby allowing for compression.

After the cylinder 21 and valve 33 have reached the end of their stroke, the valve 37 will be rotated so as to reverse the inlet, that is, steam will pass from the inlet pipe 38 through the passage 53, port 47, and out 70 through the port 38 into the passage 24 and in front of the piston 33, forcing the piston 33 and cylinder 21 back into their original positions. As this movement takes place the exhaust steam will be forced from in advance of the cylinder 21 through the port 28, 75 passage 42, port 43, passage 51, and port 18 into the exhaust pipe 50. At the same time, steam in advance of the piston 33 will be forced through the port 25, passage 33, port 31, port 46, passage 35, whence it will pass upwardly, then through the port 45, into the port 41, and through exhaust port 49 into the pipe 50.

In order to rock the valve 37 so as to bring the various passages thereon into proper alignment with the various ports, the valve 37 is provided with an axial spindle 56 upon which is secured a rocker arm 57 to which is properly connected a pitman 58 connected 90 to an eccentric mounted on the crank shaft 11. As the crank shaft is rotated, the pitman 58 will rock the arm 57, thus imparting sufficient movement to the valve 37 to operate it in unison with the movement of 95 the cylinder 21 and piston 33 for properly alining the passages in the valve 37 with the ports in the casing 30.

From the foregoing it will be apparent that I have thus provided an engine of the 100 character described, the steam circuit of which is controlled by a single valve.

It will be readily understood that various changes in the form, construction, and arrangement of parts may be resorted to without departing from the spirit of the invention or limiting the scope of the subjoined claims.

Having thus described my invention, 110 what I claim is:

1. An engine comprising a closed cylinder, a second cylinder slideable therein and provided adjacent each end with an inlet port, a piston slideable within said second named cylinder, said piston and said second named cylinder having operable connection with a crank shaft, a casing connected with said first named cylinder and provided with independent parallel passages communicating with ports adjacent the ends of said first named cylinder, a valve revolvably mounted within said casing and provided with passages for establishing communication between said parallel passages and exhaust ports in said casing, said casing being further provided with a steam inlet passage, said valve being provided with a passage adapted to establish communication between said inlet passage and with ports communicating with said first named cylinder, said 125 130

last named ports being adapted to communicate with the ports in said second named cylinder at different stages of the movement of said second named cylinder, said valve 5 being further provided with passages for establishing communication between each of said parallel passages and said second named ports.

2. An engine comprising a closed cylinder, a second cylinder slidable therein and provided upon its lower side with a pair of passages extending substantially half its length and each communicating with the interior of said second named cylinder adjacent its ends, a piston slidable within said second named cylinder, said piston and said second named cylinder having operable connection with a crank shaft, a valve casing connected with said first named cylinder 15 and provided with passages communicating with said first named cylinder adjacent its ends, a valve revolubly mounted within said casing and operably connected with said crank shaft, said valve being provided with

passages for establishing communication between said second named passages and exhaust ports in said casing, said casing being provided with a convolute passage adapted to establish communication between said inlet passage and ports formed in said first 20 named cylinder, said valve being provided with a passage for establishing communication between one of said ports and one of said second named passages and provided with an additional passage for establishing 30 communication between the other of said ports and the other of said second named passages, said ports being adapted to communicate with said first named passages at different stages of the strokes of said movable cylinder and said piston.

In testimony whereof, I affix my signature, in the presence of two witnesses.

ELIAS LUGINBUHL.
